UNITED STATES PATENT OFFICE.

GEORGE R. ANDERSON, OF SANTA ROSA, CALIFORNIA.

FRUIT DRIER.

Application filed August 3, 1925. Serial No. 47,705.

To all whom it may concern:

Be it known that I, GEORGE R. ANDERSON, a citizen of the United States, residing at Santa Rosa, county of Sonoma, and State of California, have invented new and useful Improvements in Fruit Driers, of which the following is a specification.

This invention relates to driers or dehydrators such as are employed for the purpose of drying fruit, vegetables, and other products, and especially to that type which employs warm dry air as the drying medium.

The object of the present invention is to generally improve and simplify the present operation of driers of the character described, to provide a simple, easily operated mechanism whereby the inflow and exhaust of air may be regulated, and further to provide a pre-heater whereby the incoming air may be heated by the exhausting air in such a manner as to gain the greatest heat efficiency possible.

One form which my invention may assume is exemplified in the following description and illustrated in the accompanying drawing in which—

Fig. 1 is a side elevation of the drier showing the application of the pre-heater.

Fig. 2 is a cross section of the drier taken on line II—II of Fig. 1.

Referring to the drawings in detail and particularly to Figs. 1 and 2, it will be seen that the drier consists of two inter-spaced side walls as indicated at A and B. These side walls are connected or tied together by end walls 2—2, a roof 3, and an interior floor 4 which is preferably constructed of concrete or the like to present a smooth surface. The interior of the drier is divided longitudinally into two main compartments by a central partition wall 5, and each compartment is in turn divided into an upper and a lower compartment as shown at C and D by means of a floor section 4^a the function of which will hereinafter be described. The two main compartments formed by the central partition wall 5 are identical in form and construction, and a description of one should therefore suffice. Mounted in the upper compartment is a steam radiator 6, and disposed in front

thereof is a fan or blower 7. There are two steam radiators 6 in each upper compartment, and similarly two blowers. A shaft 55 extending longitudinally in the housing is connected with each blower and the shaft is in turn connected with the driving motor 8 so that all the blowers may be driven and operated in unison. Steam is delivered to 60 the radiators from any suitable source through means of a pipe 6^a and the condensate is removed through a pipe 9. A thermostat actuated valve 10 regulates the flow of steam to each radiator, and a thermostat regulator 11 mounted on the side of the building is employed to regulate the thermostat valves; that is, each radiator is provided with a thermostat actuated valve 10 and each valve is in turn connected with 65 a thermostat regulator so that the flow of steam through each radiator may be regulated and automatically controlled. Each main compartment is also provided with a hygrometer as indicated at 12. These hygrometers are placed on the interior wall of the building in front of windows 13 from where they can be observed whenever desired. Each upper compartment is provided with a pair of air inlet pipes as indicated 70 at 14. These inlet pipes are vertically disposed on the rear side of the building and they are all connected with a common air inlet pipe which is horizontally disposed as at 15. Each upper compartment D 75 is also provided with a pair of exhaust pipes 16. These pipes are in communication with the lower compartments C. They extend vertically upwardly into the inlet pipes 14 and then extend downwardly through the same, and are finally connected with a main exhaust pipe 17 which is connected with the suction side of the blower 18. The main exhaust pipe 17 extends through the main inlet pipe 15. It is interspersed with relation thereto to form an annular air inlet passage and so are the pipes 16 which extend through the vertically disposed inlet pipes 14. The specific exhaust pipes 16 are each provided with a damper 19 and these are regulated by hand levers on the exterior of the pipes as shown at 20. The floor section 4^a which divides the main compartments into upper and lower compartments as shown at 80

100

C and D are provided with openings as indicated at 21 and 22. These openings permit a continuous circulation of the air between the upper and lower compartments 5 as indicated by the arrows; that is, the blowers 7 discharge the air forwardly through the steam radiators 6 in the direction of arrow α , the air then passes downwardly through the opening 21 and through 10 the compartment C, and is then directed outwardly through the opening 22 where it enters the suction side of the blowers 7 to be again discharged and continuously circulated. The fruit or other product to be 15 dried is placed on trays generally indicated at 24 in the lower compartments C and as the air is continuously circulated it is obvious that the product will be gradually dried as the air will pass both over and 20 under the trays.

For the purpose of readily introducing the product to be dried and removing the same from the lower drying compartments C a series of loading platforms such as indicated at 25 are employed. These platforms are handled by a special form of truck which may be passed under the platform to raise the same and support it when a load is to be moved from place to place. 25 The truck is similarly capable of being lowered to release the platform when a load has reached its destination. To appreciate this feature, it may be supposed that prunes are being dried. Prunes require considerable 30 handling and transferring from place to place, and the trucks are therefore exceedingly useful. It is first necessary to dip the prunes in a lie solution to slightly crack the peel or skin as this materially promotes 35 the drying action. It is then necessary to spread the prunes on drying trays, then to stack the trays on the loading platforms 25, then to transfer the load of platforms into the driers, then to remove them and haul 40 the same to the storage bins, etc. Many drying plants are so arranged that the trays may be stacked on cars and the cars moved on tracks, but such an installation is naturally costly and is entirely eliminated in this 45 instance as it is only necessary to provide concrete or wooden runways for the trucks and platforms there employed. The operation will be as follows: A number of trays are stacked upon a platform such as indicated at 25 (see Fig. 2). The trays are, of 50 course, interspaced and loaded with the fruit or other material to be dried. Different varieties of fruit, vegetables, and other products require varying drying temperatures, 55 and certain conditions of humidity. We will accordingly suppose that it is first desired to subject a fruit to air having a temperature of 110° F. and also that it is desired 60 to maintain a certain humidity content as far as the drying air is concerned.

If this is the case, the operator regulates the devices indicated at 11 and sets the same at 110° F. The devices 11 regulate the thermostat valves 10 and they in turn admit steam to the radiators in such quantities as 65 to cause the air within the drying compartments to assume a temperature of 110° F. The blowers 7 are simultaneously set in operation and the air will therefore continuously circulate through the trays in the direction of the arrows. The air will continue 70 to circulate and the temperature of 110° F. will be automatically maintained. The air also gradually absorbs the moisture liberated by the material being dried and the humidity content of the air therefore gradually increases, and when the humidity content reaches a predetermined point the operator who watches the hygrometers through the windows merely slightly opens the dampers 75 80 85 90 95 100 105 110 115 120 125 130

19. The exhaust blowers 18 are in continuous operation and as the exhaust pipes 16 are subjected to the suction thereof it is obvious that a small proportion of the air within the drying chamber will be exhausted or removed and will be discharged through the pipes 30 of the blower. A slight vacuum is accordingly formed within the drying compartments and fresh air from the atmosphere will automatically be drawn in through the main inlet pipe 15 and the vertical inlet pipes 14, and as such will enter and mingle with the air circulated within the drying compartments. The fresh air admitted is of course dry and the humidity content will gradually lower. The operator who is continuously watching will adjust the dampers 19 until a balance is maintained; that is, just sufficient air is continuously exhausted to permit a sufficient amount of 105 fresh air to continuously enter and thereby maintain the circulating drying air at an approximately constant humidity content. If it is desired to increase or decrease the 110 temperature of the air during the drying operation, it is only necessary for the operator to regulate the devices indicated at 11 as these in turn regulate the thermostat valves 10 and thereby increase or decrease the flow of temperature through the radiators. An 115 important feature in connection with the air control is that of preheating the incoming fresh air. If a temperature of 110° F. is maintained within the dryer it is obvious that the exhausted air will discharge at this 120 temperature. The inlet air pipes surround the exhaust pipes and the incoming air is accordingly heated both by conduction and convection. This is of material importance as the general thermal efficiency of the plant is considerably increased and a proportionate amount of fuel is saved as far as the steam radiating plant is concerned.

The end walls of the drier are provided with doors as indicated at 41 and 42. These 130

are also important as they permit ready removal and replacement of drying trays from time to time. The thermostat regulators 11 and the thermostat actuated valves 10 are 5 fully disclosed in my co-pending application entitled "Driers" filed June 11, 1923, Serial No. 644,541 and a detailed description of their construction and operation is therefore thought unnecessary. The main novel 10 feature of the present invention is the arrangement of exhaust and inlet pipes together with the dampers 19 which regulate the flow of air through the preheater. The dampers are exceedingly important as they 15 materially increase the heat efficiency of the plant and furthermore provide a single control whereby the air exhausted and the air admitted to the drying compartments is regulated. This control also determines the 20 humidity content of the air and thereby simplifies the operation of the plant.

While certain features of the present invention are more or less specifically illustrated, I wish it understood that various 25 changes in form and proportion may be resorted to within the scope of the appended claims. I similarly wish it understood that the materials and finish of the several parts employed may be such as the experience and 30 judgment of the manufacturer may dictate or various uses may demand.

Having thus described my invention, what I claim and desire to secure by Letters Patent is—

- 35 1. A drier of the character described comprising a housing having a compartment formed therein, air heating means in the compartment, means for maintaining a constant circulation and flow of air through the compartment and the heating means, concentric air inlet and exhaust pipes connected with the compartment, whereby the air is exhausted and fresh air is admitted and heated by the exhaust air, suction means connected 40 with the exhaust pipe to withdraw air from the compartment by suction, and a single means controlling the volume of air exhausted and the volume of air which is preheated and admitted to the compartment.
- 45 2. A drier of the character described comprising a housing having a compartment formed therein, air heating means in the compartment, means for maintaining a constant circulation and flow of air through the compartment and the heating means, concentric air inlet and exhaust pipes connected with the compartment, whereby the air is exhausted and fresh air is admitted and heated by the exhaust air, suction means 50 connected with the exhaust pipe to withdraw air from the compartment by suction, and a damper in the exhaust pipe controlling the volume of air exhausted and the volume of air which is preheated and admitted to the compartment.
- 55 3. A drier of the character described comprising a housing, a partition in the housing dividing it into two compartments, said partition having an opening formed in each end whereby communication is maintained 60 between the compartments, air heating means in one compartment, means for maintaining a constant circulation and flow of air through the heating means, the openings in the partition and the respective compartments, an air exhaust pipe in communication with the compartments, an air inlet pipe also communicating with the compartments said air inlet pipe enclosing the air exhaust pipe and forming an annular inlet 65 passage wherein incoming air may be preheated by the exhausting air, a suction blower connected with the exhaust pipe and a damper in said pipe to regulate the volumes of air exhausted and admitted.
- 70 4. A drier of the character described comprising a housing, a partition in the housing dividing it into two compartments, said partition having an opening formed in each end whereby communication is maintained 75 between the compartments, air heating means in one compartment, means for maintaining a constant circulation and flow of air through the heating means, the openings in the partition and the respective compartments, an air preheater, an air exhaust pipe connected with the compartment and the preheater to heat the same, an air inlet pipe connected with the preheater and the compartment, means exerting an evacuating 80 effect on the exhaust pipe to remove air from the compartments and to circulate said air through the preheater, and means for regulating the volume of air thus removed and for simultaneously admitting an equivalent volume of preheated air to the compartments.
- 85 5. A drier of the character described comprising a plurality of drying compartments, a common air exhausting pipe, pipes leading 90 therefrom to each drying compartment, a damper in each of said last named pipes, manually controlled means for opening and closing any damper, and means for replacing the air exhausted and for preheating the same by means of the exhausting air when a damper is opened and air is exhausted.
- 95 6. A drier of the character described comprising a plurality of drying compartments, a main air exhausting pipe, branch pipes leading 100 therefrom to each drying compartment, a suction blower connected with the main exhaust pipe, a damper in each branch pipe, manually controlled means for opening and closing any damper, a main air inlet pipe enclosing the main exhaust pipe and spaced therefrom to form an air inlet and preheating passage, branch air pipes leading 105 from the main air pipe and connected 110
- 115 120
- 125 130

with each compartment said last named pipes enclosing the exhaust branch pipes and spaced therefrom to form a secondary air inlet and preheating passages, said main and branch air inlet and preheating pipes forming constant communication between the exterior atmosphere and the interior of the respective compartments and adapted to automatically replace the air exhausted when the damper is opened and also automatically maintaining atmospheric pressure in each compartment. 10

GEORGE R. ANDERSON.
